(57) **ABSTRACT**

A transmission member and an anti-jamming assembly and a nail gun having the same. The transmission member comprises a rotating member configured to be driven by a driving motor to rotate, and an engaging part arranged on the rotating member. The rotating member has a plurality of pin mounting holes having at least one movable pin mounting hole. The engaging part comprises a plurality of engaging pins installed in the plurality of pin mounting holes. The plurality of engaging pins comprises at least one movable engaging pin moveably installed in at least one movable pin mounting hole. Two adjacent engaging pins define a gap therebetween. The anti-jamming assembly comprises a striker configured to strike nails out of the nail gun along a striking direction for nailing; and the transmission member

(Continued)

coupled with the striker for driving the striker to move in a direction opposite to the striking direction.

**TRANSMISSION MEMBER AND
ANTI-JAMMING ASSEMBLY AND NAIL GUN
HAVING SAME**

**CROSS-REFERENCE TO RELATED PATENT
APPLICATIONS**

This application is a continuation application of International Patent Application No. PCT/CN2022/101897, filed Jun. 28, 2022, which itself claims priority to Chinese Patent Application No. 202210178689.1, filed Feb. 25, 2022, which are hereby incorporated herein in their entireties by reference.

FIELD OF THE INVENTION

This invention relates generally to nail guns, and more particularly to a transmission member and an anti-jamming assembly and a nail gun having the same.

BACKGROUND OF THE INVENTION

The background description provided herein is for the purpose of generally presenting the context of the invention. The subject matter discussed in the background of the invention section should not be assumed to be prior art merely as a result of its mention in the background of the invention section. Similarly, a problem mentioned in the background of the invention section or associated with the subject matter of the background of the invention section should not be assumed to have been previously recognized in the prior art. The subject matter in the background of the invention section merely represents different approaches, which in and of themselves may also be inventions.

A nail gun is a fastening tool that is mostly used in construction. Currently, a widely used nail gun is an electric nail gun powered with lithium batteries. This nail gun is driven to push a piston by a driving motor and a corresponding transmission structure, and then the piston compresses power supply springs or air to store energy. When firing nails, the springs or the compressed air drives the piston to move, and thus drives the firing pin (striker) installed on the piston to strike the nails to achieve nailing.

In the existing nail guns, the transmission structure pushes the piston generally by using a rack and gear (pinion) transmission method. That is, a rack is set on the striker, and a gear is set on the driving motor. The driving motor drives the gear to rotate. Since the rack and the gear are meshed with each other, the rack will be driven to move transversely during the rotation of the gear to store energy for the compression of the power supply spring or air. When the gear rotates to a state where there is no tooth meshing with the striker, the power supply spring or air pressure will push the striker out to achieve nailing.

The existing nail guns are prone to the following problems in certain specific situations: when the tooth grooves on the rack are not accurately meshed with the gear, that is, when the teeth of the gear directly hit the rack but do not enter the tooth grooves, it will cause the teeth to get jamming. In addition, if the user is repairing and troubleshooting, the jamming may cause the nail gun to misfire and personal injury, which is not safe.

Therefore, a heretofore unaddressed need exists in the art to address the aforementioned deficiencies and inadequacies.

SUMMARY OF THE INVENTION

One of the objectives of this invention is to provide a transmission member and an anti-jamming assembly and a nail gun having the same to solve the above problems.

In one aspect of the invention, the transmission member used for a nail gun comprises a rotating member configured to be driven by a driving motor to rotate, wherein the rotating member has a plurality of pin mounting holes, 10 wherein the plurality of pin mounting holes comprises at least one movable pin mounting hole; and an engaging part arranged on the rotating member, wherein the engaging part comprises a plurality of engaging pins installed in the plurality of pin mounting holes, wherein the plurality of 15 engaging pins comprises at least one movable engaging pin moveably installed in at least one movable pin mounting hole, and wherein two adjacent engaging pins define a gap therebetween.

In one embodiment, the transmission member further 20 comprises an elastic assembly placed between the movable engaging pin and the rotating member, wherein the elastic assembly comprises a spring with one end abutting against the movable engaging pin, and the other end abutting against the rotating member.

In one embodiment, the at least one movable pin mounting hole is an oblong hole comprising an accommodating cavity, and wherein the spring is placed in the accommodating cavity.

In one embodiment, the remaining pin mounting holes are 25 in a circular shape matching with that of the engaging pins.

In one embodiment, the elastic assembly further comprises a block placed between the spring and the movable engaging pin in the accommodating cavity, and wherein one side of the block facing the spring is provided with a limiting hole in which the spring is inserted, or a limiting column on 30 which the spring is sleeved, and the other side of the block facing the movable engaging pin is provided with an active surface in contact with the movable engaging pin.

In one embodiment, the plurality of engaging pins has n 35 40 engaging pins, wherein a first gap is formed between the first engaging pin and the adjacent nth engaging pin, and among the remaining engaging pins, each engaging pin has a second gap of the same distance with the adjacent engaging pin, and the first gap is larger than the second gap.

In one embodiment, the first engaging pin is the movable 45 engaging pin.

In one embodiment, the rotating member is a circular structure having a pair of circular disks concentrically connected to one another to define a space therebetween, and 50 a shaft mounting hole defined in the center thereof, through which the rotating member is installed on the output shaft of the driving motor which operably drives the rotating member to rotate, and wherein the plurality of pin mounting holes is defined on the circumference portion of the rotating member.

In another of the invention, the nail gun for nailing 55 comprises the transmission member as disclosed above.

In yet another of the invention, the anti-jamming assembly used for controlling nail striking of a nail gun comprises 60 a striker configured to strike nails out of the nail gun along a striking direction for nailing, wherein the striker comprises a plurality of tooth grooves; and a transmission member coupled with the striker for driving the striker to move in a direction opposite to the striking direction. The transmission member comprises a rotating member configured to be driven by a driving motor to rotate, wherein the rotating member has a plurality of pin mounting holes, wherein the

plurality of pin mounting holes comprises at least one movable pin mounting hole; and an engaging part arranged on the rotating member, wherein the engaging part comprises a plurality of engaging pins installed in the plurality of pin mounting holes, wherein the plurality of engaging pins comprises at least one movable engaging pin moveably installed in at least one movable pin mounting hole, and wherein two adjacent engaging pins define a gap therebetween; and

During the rotation of the transmission member, the plurality of engaging pins is sequentially meshed with the plurality of tooth grooves to achieve an engagement between the transmission member and the striker.

In one embodiment, each tooth groove has a guiding portion for guiding an engaging pin to enter the tooth groove, and an engaging portion extending from the guiding portion for snap-fitting with the engaging pin to achieve the engagement.

In one embodiment, the guiding portion is formed in an arc-straight-line profile including an inclined arc shape and a straight line being tangent to the inclined arc shape, and wherein the engaging portion includes a retaining edge smoothly extended from the straight line of the guiding portion with a profile matching that of the engaging pin.

In one embodiment, the number of the tooth grooves is greater than or equal to the number of the engaging pins.

In one embodiment, the transmission member further comprises an elastic assembly placed between the movable engaging pin and the rotating member, wherein the elastic assembly comprises a spring with one end abutting against the movable engaging pin, and the other end abutting against the rotating member.

In one embodiment, the at least one movable pin mounting hole is an oblong hole comprising an accommodating cavity, and wherein the spring is placed in the accommodating cavity.

In one embodiment, the remaining pin mounting holes are in a circular shape matching with that of the engaging pins.

In one embodiment, the elastic assembly further comprises a block placed between the spring and the movable engaging pin in the accommodating cavity, and wherein one side of the block facing the spring is provided with a limiting hole in which the spring is inserted, or a limiting column on which the spring is sleeved, and the other side of the block facing the movable engaging pin is provided with an active surface in contact with the movable engaging pin.

In one embodiment, the plurality of engaging pins has n engaging pins, wherein a first gap is formed between the first engaging pin and the adjacent nth engaging pin, and among the remaining engaging pins, each engaging pin has a second gap of the same distance with the adjacent engaging pin, and the first gap is larger than the second gap.

In one embodiment, the rotating member is a circular structure having a pair of circular disks concentrically connected to one another to define a space therebetween, and a shaft mounting hole defined in the center thereof, through which the rotating member is installed on the output shaft of the driving motor which operably drives the rotating member to rotate, and wherein the plurality of pin mounting holes is defined on the circumference portion of the rotating member.

In a further aspect of the invention, the nail gun for nailing comprises the anti-jamming assembly as disclosed above.

According to the transmission member and the anti-jamming assembly for the nail gun of the invention, since the transmission member includes a rotating member and an engaging part. The rotating member is used to be connected

to the driving motor of the nail gun and driven to rotate by the driving motor. The engaging part includes a plurality of engaging pins disposed in the rotating member. The engaging pins are engaged with the tooth grooves of the striker to achieve the engagement between the transmission member and the striker, so as to drive the striker to move. Compared with the engagement of the gear and the rack, the engagement of the engaging pins and the tooth grooves is easier, so the transmission is more stable. When the transmission member and the striker are engaged with each other, the engaging pins need to be embedded one by one in the tooth grooves of the striker. Conventionally, the engaging pins and the tooth grooves may not be completely aligned, resulting in the engaging pins directly colliding with the tooth block and being unable to engage and drive normally, resulting in jamming. However, according to the invention, at least one of the engaging pins is set to be movable. When the movable engaging pin collides with the tooth block, the movable engaging pin will move slightly under the action of the impact force and be accurately meshed into the tooth groove, thereby preventing the transmission member and the striker from getting jamming, thereby avoiding personal injury caused by misfiring of the gun nail due to the jamming, and further enhancing safety.

These and other aspects of the invention will become apparent from the following description of the preferred embodiment taken in conjunction with the following drawings, although variations and modifications therein may be affected without departing from the spirit and scope of the novel concepts of the disclosure.

BRIEF DESCRIPTION OF THE DRAWINGS

The accompanying drawings illustrate one or more embodiments of the invention and together with the written description, serve to explain the principles of the invention. Wherever possible, the same reference numbers are used throughout the drawings to refer to the same or like elements of an embodiment.

FIG. 1 shows schematically a perspective view of a nail gun according to one embodiment of the invention.

FIG. 2 shows schematically another perspective view of the nail gun shown in FIG. 1, after the casing is removed.

FIG. 3 shows schematically a perspective view of a driving mechanism according to one embodiment of the invention.

FIG. 4 shows schematically a cross sectional view of the driving mechanism shown in FIG. 3.

FIG. 5 shows schematically a partially exploded view of a driving mechanism according to one embodiment of the invention.

FIG. 6A is a schematic diagram of the structure of the transmission member according to one embodiment of the invention.

FIG. 6B is a cross-sectional view of the M-M direction of FIG. 6A.

FIG. 7 is a cross-sectional view of the front end portion of the driving mechanism according to one embodiment of the invention.

FIG. 8 is a cross-sectional view of an anti-jamming assembly in a working state according to one embodiment of the invention.

FIG. 9 is another cross-sectional view of the anti-jamming assembly in the working state according to one embodiment of the invention.

FIG. 10 shows schematically a perspective view of a cooperation structure of a transmission mechanism and a striking mechanism according to one embodiment of the invention.

FIG. 11 shows schematically a partial enlarged view of part A shown in FIG. 3.

FIG. 12 shows schematically a partial enlarged view of part B shown in FIG. 4.

FIG. 13 shows schematically a partial enlarged view of part C shown in FIG. 4.

FIG. 14 shows schematically a partial enlarged view of part D shown in FIG. 4.

FIG. 15 shows schematically a perspective view of an outer cylinder body according to one embodiment of the invention.

FIG. 16 shows schematically a cross sectional view of an outer cylinder body according to one embodiment of the invention.

FIG. 17 shows schematically a perspective view of an inner cylinder body according to one embodiment of the invention.

FIG. 18 shows schematically a partial enlarged view of part E shown in FIG. 4.

DETAILED DESCRIPTION OF THE INVENTION

The invention will now be described more fully herein-after with reference to the accompanying drawings, in which exemplary embodiments of the invention are shown. This invention may, however, be embodied in many different forms and should not be construed as limited to the embodiments set forth herein. Rather, these embodiments are provided so that this disclosure will be thorough and complete, and will fully convey the scope of the invention to those skilled in the art. Like reference numerals refer to like elements throughout.

The terms used in this specification generally have their ordinary meanings in the art, within the context of the invention, and in the specific context where each term is used. Certain terms that are configured to describe the invention are discussed below, or elsewhere in the specification, to provide additional guidance to the practitioner regarding the description of the invention. For convenience, certain terms may be highlighted, for example using italics and/or quotation marks. The use of highlighting has no influence on the scope and meaning of a term; the scope and meaning of a term is the same, in the same context, whether or not it is highlighted. It will be appreciated that same thing can be said in more than one way. Consequently, alternative language and synonyms may be used for any one or more of the terms discussed herein, nor is any special significance to be placed upon whether or not a term is elaborated or discussed herein. Synonyms for certain terms are provided. A recital of one or more synonyms does not exclude the use of other synonyms. The use of examples anywhere in this specification including examples of any terms discussed herein is illustrative only, and in no way limits the scope and meaning of the invention or of any exemplified term. Likewise, the invention is not limited to various embodiments given in this specification.

It will be understood that when an element is referred to as being "on" another element, it can be directly on the other element or intervening elements may be present therebetween. In contrast, when an element is referred to as being "directly on" another element, there are no intervening

elements present. As used herein, the term "and/or" includes any and all combinations of one or more of the associated listed items.

It will be understood that, although the terms first, second, third etc. may be used herein to describe various elements, components, regions, layers and/or sections, these elements, components, regions, layers and/or sections should not be limited by these terms. These terms are only configured to distinguish one element, component, region, layer or section from another element, component, region, layer or section. Thus, a first element, component, region, layer or section discussed below could be termed a second element, component, region, layer or section without departing from the teachings of the invention.

The terminology used herein is for the purpose of describing particular embodiments only and is not intended to be limiting of the invention. As used herein, the singular forms "a", "an" and "the" are intended to include the plural forms as well, unless the context clearly indicates otherwise. It will be further understood that the terms "comprises" and/or "comprising," or "includes" and/or "including" when used in this specification, specify the presence of stated features, regions, integers, steps, operations, elements, and/or components, but do not preclude the presence or addition of one or more other features, regions, integers, steps, operations, elements, components, and/or groups thereof.

Furthermore, relative terms, such as "lower" or "bottom" and "upper" or "top," may be used herein to describe one element's relationship to another element as illustrated in the Figures. It will be understood that relative terms are intended to encompass different orientations of the device in addition to the orientation depicted in the Figures. For example, if the device in one of the figures is turned over, elements described as being on the "lower" side of other elements would then be oriented on "upper" sides of the other elements. The exemplary term "lower", can therefore, encompasses both an orientation of "lower" and "upper," depending of the particular orientation of the figure. Similarly, if the device in one of the figures is turned over, elements described as "below" or "beneath" other elements would then be oriented "above" the other elements. The exemplary terms "below" or "beneath" can, therefore, encompass both an orientation of above and below.

Unless otherwise defined, all terms (including technical and scientific terms) used herein have the same meaning as commonly understood by one of ordinary skill in the art to which this invention belongs. It will be further understood that terms, such as those defined in commonly used dictionaries, should be interpreted as having a meaning that is consistent with their meaning in the context of the relevant art and the present disclosure, and will not be interpreted in an idealized or overly formal sense unless expressly so defined herein.

It will be understood that when an element is referred to as being "on", "attached" to, "connected" to, "coupled" with, "contacting", etc., another element, it can be directly on, attached to, connected to, coupled with or contacting the other element or intervening elements may also be present.

In contrast, when an element is referred to as being, for example, "directly on", "directly attached" to, "directly connected" to, "directly coupled" with or "directly contacting" another element, there are no intervening elements present. It will also be appreciated by those of skill in the art that references to a structure or feature that is disposed "adjacent" another feature may have portions that overlap or underlie the adjacent feature.

As used herein, "around", "about", "substantially" or "approximately" shall generally mean within 20 percent, preferably within 10 percent, and more preferably within 5 percent of a given value or range. Numerical quantities given herein are approximate, meaning that the term "around", "about" "substantially" or "approximately" can be inferred if not expressly stated.

As used in this specification, the phrase "at least one of A, B, and C" should be construed to mean a logical (A or B or C), using a non-exclusive logical OR. As used herein, the term "and/or" includes any and all combinations of one or more of the associated listed items.

Embodiments of the invention are illustrated in detail hereinafter with reference to accompanying drawings. The description below is merely illustrative in nature and is in no way intended to limit the invention, its application, or uses. The broad teachings of the invention can be implemented in a variety of forms. Therefore, while this invention includes particular examples, the true scope of the invention should not be so limited since other modifications will become apparent upon a study of the drawings, the specification, and the following claims. For purposes of clarity, the same reference numbers will be used in the drawings to identify similar elements. It should be understood that one or more steps within a method may be executed in different order (or concurrently) without altering the principles of the invention.

In accordance with the purposes of this invention, as embodied and broadly described herein, this invention, in certain aspects, relates to a transmission member and an anti-jamming assembly and a nail gun having the same.

In one embodiment, the transmission member used for a nail gun comprises a rotating member configured to be driven by a driving motor to rotate, wherein the rotating member has a plurality of pin mounting holes, wherein the plurality of pin mounting holes comprises at least one movable pin mounting hole; and an engaging part arranged on the rotating member, wherein the engaging part comprises a plurality of engaging pins installed in the plurality of pin mounting holes, wherein the plurality of engaging pins comprises at least one movable engaging pin moveably installed in at least one movable pin mounting hole, and wherein two adjacent engaging pins define a gap therebetween.

In one embodiment, the transmission member further comprises an elastic assembly placed between the movable engaging pin and the rotating member, wherein the elastic assembly comprises a spring with one end abutting against the movable engaging pin, and the other end abutting against the rotating member.

In one embodiment, the at least one movable pin mounting hole is an oblong hole comprising an accommodating cavity, and wherein the spring is placed in the accommodating cavity.

In one embodiment, the remaining pin mounting holes are in a circular shape matching with that of the engaging pins.

In one embodiment, the elastic assembly further comprises a block placed between the spring and the movable engaging pin in the accommodating cavity, and wherein one side of the block facing the spring is provided with a limiting hole in which the spring is inserted, or a limiting column on which the spring is sleeved, and the other side of the block facing the movable engaging pin is provided with an active surface in contact with the movable engaging pin.

In one embodiment, the plurality of engaging pins has n engaging pins, wherein a first gap is formed between the first engaging pin and the adjacent nth engaging pin, and among

the remaining engaging pins, each engaging pin has a second gap of the same distance with the adjacent engaging pin, and the first gap is larger than the second gap.

In one embodiment, the first engaging pin is the movable engaging pin.

In one embodiment, the rotating member is a circular structure having a pair of circular disks concentrically connected to one another to define a space therebetween, and a shaft mounting hole defined in the center thereof, through which the rotating member is installed on the output shaft of the driving motor which operably drives the rotating member to rotate, and wherein the plurality of pin mounting holes is defined on the circumference portion of the rotating member.

In one embodiment, the nail gun for nailing comprises the transmission member as disclosed above.

In one embodiment, the anti-jamming assembly used for controlling nail striking of a nail gun comprises a striker configured to strike nails out of the nail gun along a striking direction for nailing, wherein the striker comprises a plurality of tooth grooves; and a transmission member coupled with the striker for driving the striker to move in a direction opposite to the striking direction. The transmission member comprises a rotating member configured to be driven by a driving motor to rotate, wherein the rotating member has a plurality of pin mounting holes, wherein the plurality of pin mounting holes comprises at least one movable pin mounting hole; and an engaging part arranged on the rotating member, wherein the engaging part comprises a plurality of engaging pins installed in the plurality of pin mounting holes, wherein the plurality of engaging pins comprises at least one movable engaging pin moveably installed in at least one movable pin mounting hole, and wherein two adjacent engaging pins define a gap therebetween; and

During the rotation of the transmission member, the plurality of engaging pins is sequentially meshed with the plurality of tooth grooves to achieve an engagement between the transmission member and the striker.

In one embodiment, each tooth groove has a guiding portion for guiding an engaging pin to enter the tooth groove, and an engaging portion extending from the guiding portion for snap-fitting with the engaging pin to achieve the engagement.

In one embodiment, the guiding portion is formed in an arc-straight-line profile including an inclined arc shape and a straight line being tangent to the inclined arc shape, and wherein the engaging portion includes a retaining edge smoothly extended from the straight line of the guiding portion with a profile matching that of the engaging pin.

In one embodiment, the number of the tooth grooves is greater than or equal to the number of the engaging pins.

In one embodiment, the transmission member further comprises an elastic assembly placed between the movable engaging pin and the rotating member, wherein the elastic assembly comprises a spring with one end abutting against the movable engaging pin, and the other end abutting against the rotating member.

In one embodiment, the at least one movable pin mounting hole is an oblong hole comprising an accommodating cavity, and wherein the spring is placed in the accommodating cavity.

In one embodiment, the remaining pin mounting holes are in a circular shape matching with that of the engaging pins.

In one embodiment, the elastic assembly further comprises a block placed between the spring and the movable engaging pin in the accommodating cavity, and wherein one side of the block facing the spring is provided with a limiting

hole in which the spring is inserted, or a limiting column on which the spring is sleeved, and the other side of the block facing the movable engaging pin is provided with an active surface in contact with the movable engaging pin.

In one embodiment, the plurality of engaging pins has n engaging pins, wherein a first gap is formed between the first engaging pin and the adjacent nth engaging pin, and among the remaining engaging pins, each engaging pin has a second gap of the same distance with the adjacent engaging pin, and the first gap is larger than the second gap.

In one embodiment, the rotating member is a circular structure having a pair of circular disks concentrically connected to one another to define a space therebetween, and a shaft mounting hole defined in the center thereof, through which the rotating member is installed on the output shaft of the driving motor which operably drives the rotating member to rotate, and wherein the plurality of pin mounting holes is defined on the circumference portion of the rotating member.

In one embodiment, the nail gun for nailing comprises the anti-jamming assembly as disclosed above.

Without intent to limit the scope of the invention, exemplary embodiments of the invention are now described in conjunction with the accompanying drawings in FIGS. 1-18.

Referring to FIGS. 1-2, a nail gun 10 is schematically shown according to one embodiment of the invention, which is more convenient to operate and can improve safety and nail firing effect.

The nail gun 10 in the exemplary embodiment includes a housing 20, a nail magazine assembly 30 for storing nails, a driving mechanism 40 for driving a striking mechanism 41 to fire nails, and a control device 50 for controlling the driving mechanism 40 to operate. As shown in FIGS. 1-2, the housing 20 includes a casing 21. The nail magazine assembly 30 is disposed at a front end of the casing 21. The control device 50 includes components such as batteries, control boards, circuits, switches, and motors (not shown), all of which are installed inside and/or on the inner surface of the casing 21. Accordingly, the casing 21 can not only accommodate internal components such as the driving mechanism 40 and the control device 50, but also protect these internal components.

The driving mechanism 40 is arranged inside the casing 21 and is configured to act on the nail gun 10 to fire the nails. As shown in FIGS. 3-5, the driving mechanism 40 includes a striking mechanism 41 configured to strike the nails out for nailing, an energy storage mechanism 42 configured to provide the driving force (power), and a transmission mechanism 43 configured to transmit the driving force to drive the striking mechanism 41.

The striking mechanism 41 can be driven to operably move in a striking direction for striking the nails out, where the striking direction is the direction in which the nails are nailed into the nailed object. The energy storage mechanism 42 operably drives the striking mechanism 41 to carry out a forward movement along the striking direction to strike the nails. The transmission mechanism 43 operably drives the striking mechanism 41 to reversely move along the striking direction, thereby triggering the energy storage mechanism 42 to store energy therein.

The striking mechanism 41 has a striker 411 and a piston 412. The rear (inner) end of the striker 411 is installed (e.g., inserted) on the piston 412, so that the striker 411 and the piston 412 are co-movably connected to each other. The piston 412 is moveably arranged inside the energy storage mechanism 42. The front (outer) end of the striker 411

extends out of the energy storage mechanism 42 for striking the nails along the striking direction (i.e., the forward direction).

The transmission mechanism 43 has a transmission member 431 and a limiting member 432. The transmission member 431 is configured to engage with the striker 411 to form an anti-jamming assembly. The transmission member 431 can rotate under the drive of the motor, and the rotation of the transmission member 431 drives the striker 411 to move in an opposite direction (i.e., the backward direction) of the striking direction. The limiting member 432 is configured to engage with the transmission member 431 to limit the movement of the striker 411, particularly prevent the striker 411 from misfiring, e.g., moving in the striking direction when storing energy. The transmission member 431 is provided with a limiting structure 433 that engages with the limiting member 432.

FIGS. 5-10 schematically show the engagements of the transmission mechanism 43 with the striking mechanism 41 according to one embodiment of the invention.

As shown in FIGS. 5 and 7-10, one side of the striker 411 is provided with several tooth blocks 4111, and tooth grooves 4112 are formed between adjacent tooth blocks 4111. As shown in FIGS. 6A and 6B, the transmission member 431 includes a rotating member 4311 and an engaging part 4312. The rotating member 4311 is a circular structure having a pair of circular disks 4311a and 4311b (FIG. 5) concentrically connected to one another to define a space therebetween, and a shaft mounting hole 43111 defined in the center thereof, through which the rotating member 4311 is installed on the output shaft 51 of the driving motor (not shown) which operably drives the rotating member 4311 to rotate. The engaging part includes a plurality of engaging pins (pinions) 4312 arranged between the pair of circular disks 4311a and 4311b of the rotating member 4311. Specifically, the rotating member 4311 has a plurality of pin mounting holes 43110 defined on its circumference portion, and the plurality of engaging pins 4312 is respectively disposed/inserted in the plurality of pin mounting holes 43110 (FIG. 6A). The engaging pins 4312 are operably received by (engaged with) the tooth grooves 4112 on the striker 411, as shown in FIG. 8, thereby realizing the engagement between the transmission member 431 and the striker 411. When the rotating member 4311 is driven by the driving motor to rotate counterclockwise, the engaging pins 4312 of the transmission member 431 are sequentially embedded (meshed or mated) in the tooth grooves 4112 of the striker 411, thereby driving the striker 411 to move in a direction opposite to the striking direction of the striker 411. When the rotating member 4311 rotates counterclockwise, the sequential engagement of the engaging pins 4312 with the tooth grooves 4112 on the striker 411 drives the striker 411 to move to in a backward direction, as shown by the arrow D2 in FIGS. 8-10, which is opposite of the striking direction D1 (i.e., the forward direction), as shown in FIG. 8.

As shown in FIGS. 8-9, the plurality of engaging pins 4312 includes at least one movable engaging pin (pinion) 4312'. The plurality of pin mounting holes 43110 of the rotating member 4311 includes an oblong hole 43112 configured to receive the movable engaging pin 4312' and allow the movable engaging pin 4312' to operably move therein. The other pin mounting holes 43110 are in a circular shape matching with that of the engaging pin 4312. An elastic assembly is provided between the movable engaging pin 4312' and the rotating member 4311. The elastic assembly has a first spring 441 with one end acting on (abutting

against) the rotating member 4311, and the other end acting on (abutting against) the movable engaging pin 4312'. In one embodiment, the oblong hole 43112 is of an accommodating cavity 43113 (FIG. 6B). The first spring 441 is installed and accommodated in the accommodating cavity 43113. The elastic assembly also has a top block 442 located between the first spring 441 and the movable engaging pin 4312' in the accommodating cavity 43113. The side of the top block 442 facing the first spring 441 is provided with a limiting hole 4421 in which the first spring 441 is inserted, or a limiting column on which the first spring 441 is sleeved. The side of the top block 442 facing the movable engaging pin 4312' is provided with an active surface in contact with the movable engaging pin 4312'.

In one embodiment, the plurality of engaging pins 4312 has n engaging pins. Each engaging pin 4312 of the transmission member 431 corresponds to a tooth groove 4112 of the striker 411 one by one. In one embodiment, nine (9) engaging pins 4312 (4312') are utilized. The movable engaging pin 4312' of the transmission member 431 is used as the first engaging pin that is meshed into the first tooth groove 4112' of the striker 411. Among them, setting the first engaging pin to be movable ensures that the first engaging pin can be better embedded in the first tooth groove 4112' of the striker 411.

For example, when triggered, if the movable engaging pin 4312' is just in contact with the tooth block 4111 of the striker 411, since the movable engaging pin 4312' is set to be movable, the movable engaging pin 4312' will be pushed to move slightly in the oblong hole 43112 under the reaction force of the tooth block 4111, and then inserted into the first tooth groove 4112' of the striker 411 under the action of the first spring 441 (as shown in FIG. 8), so that the first engaging pin 4312' and the first tooth groove 4112' are engaged with each other normally, thereby avoiding situations such as jamming. When the engaging pins 4312 follow the rotating member 4311 to continuously rotate counterclockwise, each engaging pin is sequentially inserted into each corresponding tooth groove, thereby driving the striker 411 to move in the direction D2 that is opposite of the striking direction D1, as shown in FIG. 9.

In the clockwise direction, a first gap L1 is defined between the first engaging pin 4312' and the n-th engaging pin 4312". In the counterclockwise direction, the engaging pins 4312 between the first engaging pin 4312' and the n-th engaging pin 4312" are evenly arranged at the circumference/edge portion of the rotating member 4311, such that two adjacent engaging pins 4312 define a second gap L2 of the same distance therebetween. The first gap L1 is larger than the second gap L2. When the rotating member 4311 rotates to the first gap L1 towards the striker 411, the rotating member 4311 and the striker 411 are in an empty tooth state at this point, i.e., the rotating member 4311 and the striker 411 are disengaged from each other, since there is no engaging pin in the first gap L1. Accordingly, the striker 411 in this state can be triggered by the energy storage mechanism 42 to move along the striking direction, thereby firing the nails. In addition, there is the same distance between adjacent tooth grooves 4112 of the striker 411, which has a corresponding relationship with the second gap L2. In one embodiment, the lateral length between adjacent tooth grooves 4112 is almost equal to the arc length of the second gap L2, so that each engaging pin 4312 is corresponding to each tooth groove 4112.

As shown in FIG. 8, the tooth groove 4112 between the tooth blocks 4111 has a guiding portion 4112a and an engaging portion 4112b extending from the guiding portion

4112a. The guiding portion 4112a is formed in an arc-straight-line profile including an inclined arc shape and a straight line being tangent to the inclined arc shape for guiding the engaging pin 4312 to enter the tooth groove 4112. The engaging portion 4112b smoothly extends from the inner end of the guiding portion 4112a. The engaging portion 4112b includes a retaining edge smoothly extended from the straight line of the guiding portion 4112a with a profile matching that of the engaging pin 4312 for snap-fitting with the engaging pin 4312 to achieve the engagement therewith. During the rotation of the rotating member 4311, each engaging pin 4312 slides into the engaging portion 4112b along the guiding portion 4112a of the corresponding tooth groove 4112. Under the blocking action of the retaining edge, the engaging pin 4312 pushes the striker 411 to move while following the rotation of the rotating member 4311. The number of the tooth grooves 4112 is greater than or equal to the number of the engaging pins 4312, so that there is an empty tooth state between the engaging pins and the tooth grooves, in which the striker can drive the nail out along the striking direction.

As shown in FIG. 10, the limiting structure 433 is a ratchet coaxially and co-movably arranged with the rotating member 4311. Both the ratchet 433 and the rotating member 4311 are sleeved on the output shaft 51 of the driving motor and are fixedly connected together so that the ratchet 433 operably rotates synchronously with the rotating member 4311 under the drive of the driving motor. The outer circumference of the ratchet 433 is provided with a number of ratchet teeth 4331. The limiting member 432 has a pawl 4321 that is configured to be inserted between adjacent ratchet teeth 4331 to engage with the ratchet teeth 4331. As shown in FIG. 10, the distance between adjacent ratchet teeth 4331 of the ratchet 433 is smaller than the groove width (i.e., a distance between two adjacent of the tooth grooves 4111 of the striker 411, as shown in FIG. 8), so that the pawl 4321 and the ratchet teeth 4331 can be more tightly and securely engaged when mated, thereby preventing from falling out. It should be noted that, in actual practice, the distance between adjacent ratchet teeth 4331 may also be set to be equal to the width of the tooth groove 4112, which can also achieve the same matching effect, but the matching tightness is not as good as the effect of setting the distance between adjacent ratchet teeth 4331 to be smaller than the groove width of the tooth groove 4112.

In the exemplary embodiment, since the distance between the ratchet teeth 4331 is much smaller than the width of the tooth groove 4112, the mutual engagement between the pawl 4321 and the ratchet teeth 4331 is much tighter and firmer. Compared with the prior art where the ratchet is directly matched with the tooth groove 4112, the problem of ratchet detachment in the prior art will not occur according to the invention. Of course, setting the spacing between adjacent ratchets 4331 to be equal to or greater than the width of the tooth grooves 4112 can also achieve a position-limiting effect, but its effect is much less than that of the adjacent ratchet teeth 4331 with the spacing therebetween being less than the width of the tooth groove 4112.

In some embodiments, the limiting structure 433 can also be a ratchet that is integrally provided directly on the rotating member 4311, that is, the rotating member 4311 is set to be thicker, and the ratchet is directly arranged on the outer circumference of the upper part of the rotating member 4311. Such an arrangement can not only ensure that the limiting structure 433 and the rotating member 4311 keep synchronous rotation, but also reduce parts. However, the

arrangement may have higher requirements on the manufacture of the ratchet and the rotating member.

As shown in FIG. 4, the energy storage mechanism 42 includes an energy storage member 45, an inflatable member 46 and a pressure relief member 47. The energy storage member 45 has an outer cylinder 451 and an inner cylinder 452. The outer cylinder 451 includes an outer cylinder body 4511 and a rear cover 4512 detachably attached onto the rear end of the outer cylinder body 4511 to cover the outer cylinder body 4511. The inner side of the outer cylinder body 4511 forms an air chamber 453. In one embodiment, the air chamber 453 is formed between the outer cylinder 451 and the inner cylinder 452.

The inner cylinder 452 has a long cylindrical structure and is installed inside the outer cylinder body 4511. The striking mechanism 41 is installed inside the inner cylinder 452. The outer circumference of the piston 412 of the striking mechanism 41 is close to the inner wall of the inner cylinder 452, and a second sealing member (e.g., sealing ring) 413 is pressed between the piston 412 and the inner wall of the inner cylinder 452. The piston 412 is fixed with a striker 411, and the front end of the striker 411 extends out of the inner cylinder 452, and the front end of the outer cylinder body 4511 is engaged with the transmission member 431.

As shown in FIG. 4, the piston 412 and the second sealing member 413 divide the interior of the inner cylinder 452 into two separate parts, i.e., a first cavity 4521 and a second cavity 4522, and the volumes of the first cavity 4521 and the second cavity 4522 change during the moving of the piston 412. The second cavity 4522 is in fluidic communication with the air chamber 453. The first cavity 4521 is separated from the second cavity 4522 and is in fluidic communication with the outside environment. The front end of the inner cylinder 452 is provided with an inner through hole 4523 that connects the first cavity 4521 with the outside environment. The rear cover 4512 is configured in a detachable form to facilitate the disassembly of the outer cylinder body 4511 to replace or repair the striking mechanism 41. To form a sealed space (state) inside the air chamber 453, a first sealing member 4513 is placed at the connection between the rear cover 4512 and the outer cylinder body 4511 to enhance the tightness of the connection between the rear cover 4512 and the outer cylinder body 4511 and avoid the generation of air leakage in the air chamber 453. In one embodiment, a sealing ring is used as the first sealing member 4513, as shown in FIG. 12.

In some embodiments, the air chamber 453 is filled with air or nitrogen. Since the striking mechanism 41 is installed inside the inner cylinder 452, when the striker 411 is driven by the transmission member 431 to move, the piston 412 will move towards the direction of the second cavity 4522, the volume of the second cavity 4522 gradually decreases, so that the air in the air chamber 453 is compressed, and the air pressure inside the air chamber 453 gradually increases, thereby realizing energy storage. When the rotating member 4311 of the transmission member 431 rotates to the second gap and faces the striker 411, that is, when the striker 411 is in the empty tooth state, under the air pressure in the air chamber 453, the striking mechanism 41 is pushed out along the striking direction, thereby realizing nailing.

To replenish the air in the air chamber 453 conveniently, the inflatable member 46 is specially provided at the rear end of the outer cylinder body 4511 close to the rear cover 4512. As shown in FIGS. 4 and 12, the outer cylinder body 4511 is provided with an air inlet 4514 near the rear cover 4512, and an air inlet passage 4531 connecting the air chamber 453

and the air inlet 4514 is provided on the outer cylinder body 4511 on the side of the air inlet 4514.

The inflatable member 46 is an inflatable nozzle with an inflatable channel 461 in the middle, one end of the inflatable nozzle is inserted at the air inlet 4514, and the other end extends out of the outer cylinder body 4511 and is exposed on the outside environment, which is convenient for users to inflate the inflatable nozzle.

As shown in FIGS. 4 and 13, one side of the front end of the outer cylinder body 4511 is provided with a pressure relief member 47. In one embodiment, the pressure relief member 47 is an automatic pressure relief valve. When the air pressure in the air chamber 453 gradually increases and reaches a preset threshold value, the automatic pressure relief valve will automatically open to release the pressure in the air chamber 453, so that the air pressure in the air chamber 453 is always kept within the threshold value, thereby ensuring the safety inside the outer cylinder body 4511. In addition, the outer end of the pressure relief member 47 is exposed on the outside of the outer cylinder body 4511. When the user needs to disassemble and inspect the outer cylinder body, the pressure relief valve can also be opened manually to discharge the air inside the air chamber 453 before disassembly, thereby avoiding the high air pressure inside the air chamber 453 to cause the striker 411 to be accidentally fired and hurt the user, and enhancing the safety of the nail gun.

Specifically, as shown in FIG. 13, a pressure relief port 4515 is provided on one side of the front end of the outer cylinder body 4511, and a pressure relief channel 4532 connecting the pressure relief port 4515 and the air chamber 453 is provided on the outer cylinder body 4511. The automatic pressure relief valve has a pressure relief valve body 471, a pressure relief valve core 472, and a pressure relief spring 473. One end of the pressure relief valve body 471 is fixedly installed in the pressure relief port 4515, and the other end extends out and is exposed outside the outer cylinder body 4511. The middle portion of the pressure relief valve body 471 is provided with a pressure relief chamber 474 fluidically communicating with the pressure relief port 4515, and the side of the pressure relief valve body 471 is provided with a pressure relief hole 475 communicating with the pressure relief chamber 474 and the outside environment. The pressure relief valve core 472 is disposed in the pressure relief chamber 474 and is moveable therein by the pressure relief spring 473. The side wall of the pressure relief chamber 474 is formed with a limiting and blocking surface 4741 that operably engages with the pressure relief valve core 472. When the automatic pressure relief valve is closed, the pressure relief valve core 472 is blocked at the connection between the pressure relief chamber 474 and the pressure relief port 4515 under the action of the pressure relief spring 473. At this point, the pressure relief valve core 472 and the limiting and blocking surface 4741 is in tight contact with each other, and the air in the air chamber 453 cannot be discharged. When the air pressure in the air chamber 453 gradually increases and exceeds the preset threshold value, the air from the air chamber 453 will enter into the pressure relief chamber 474 through the pressure relief channel 4532 and the pressure relief port 4515 and gradually pushes the pressure relief valve core 472. When the pressure relief valve core 472 is pushed away from the limiting and blocking surface 4741 to form a gap therebetween, the air can pass through the gap and be discharged from the pressure relief hole 475, thereby releasing the pressure inside the air chamber 453. When the air pressure in the air chamber 453 drops to a preset threshold value,

under the action of the pressure relief spring 473, the pressure relief valve core 472 will be pushed back to make it in tight contact with the limiting and blocking surface 4741. The automatic pressure relief valve does not need to be activated manually during operation and can be automatically opened according to changes inside the air chamber 453 to protect the air chamber 453.

As shown in FIG. 4, the front end of the inner cylinder 452 is fixedly connected to the front end of the outer cylinder 451, and a buffer pad 454 is provided at the joint of them. The buffer pad 454 is configured to provide blocking and buffering for the piston 412 to prevent it from directly colliding with the inner surface of the outer cylinder body and protect the piston 412. In one embodiment, the middle portion of the buffer pad 454 is provided with a through hole 4541 through which the front end of the striker 411 is extended. The inner end surface of the buffer pad 454 is used for buffering the piston 412. When the piston 412 is pushed forward by the air pressure in the air chamber 453 to move forward in the striking direction, and the piston 412 can move until it is blocked by the buffer pad 454.

In some embodiments, as shown in FIGS. 13 and 14, the specific installation structure of the buffer pad 454 is as follows: the inner cylinder 452 is a long cylindrical structure; the outer circumference of the buffer pad 454 is formed with a mounting convex ring 4542; the inner side of the front end of the outer cylinder body 4511 is provided with a limiting surface 4516 and a limiting boss 4517 (FIG. 16); the front end of the buffer pad 454 abuts against the limiting surface 4516 (FIG. 4); and the front end surface of the inner cylinder 452 abuts against the mounting convex ring 4542 and the limiting boss 4517, thereby realizing the connections between the buffer pad 454, the inner cylinder 452 and the outer cylinder body 4511.

As shown in FIG. 14, a third sealing member 455 is provided between the outer circumference of the inner cylinder 452 and the inner wall of the outer cylinder body 4511. In one embodiment, the third sealing member 455 is two sealing rings. The front end of the outer cylinder body 4511 is provided with an outer through hole 4518 outside the inner through hole 4523. The inner through hole 4523 and the outer through hole 4518 are connected, thereby connecting the first cavity 4521 with the outside environment.

In the transverse section, the inner through hole 4523 and the outer through hole 4518 are located at the front side of the third sealing member, the air chamber 453 is located at the rear side of the third sealing member, such that the third sealing member 455 can not only strengthen the tightness of the connection, but also separates the air chamber 453 from the first cavity 4521 to form two independent spaces, so as to prevent the air chamber 453 from communicating with the outside environment and being affected by the external air pressure.

As shown in FIG. 15, the front end of the outer cylinder body 4511 is provided with a mounting portion 4519. The mounting portion 4519 includes a recess 4519a formed for mounting the transmission member 431 thereon. The recess 4519a has a shape configured to match that of the rotating member 431 of the transmission member 431, i.e., a circular shape. The mounting portion 4519 also includes a mounting groove 4519b formed on one side of the recess 4519a, wherein as assembled, the pawl 4321 of the limiting member 432 is accommodated in the mounting groove 4519b. The side wall of the recess 4519a facing the mounting groove 4519b is provided with a hole 4519c for one end of the pawl 4321 to pass through.

As shown in FIG. 11, the pawl 4321 has a positioning end 4321a, a limiting end 4321b and a middle portion 4321c formed between the positioning end 4321a and the limiting end 4321b. The positioning end 4321a is rotatably mounted on the mounting groove 4519b through a rotating shaft 4321d. The limiting end 4321b passes through the hole 4519c on the side wall of the recess 4519a and extends into the recess 4519a and engages with the ratchet teeth 4331 of the ratchet 433 installed in the recess 4519a. A second spring 4322 is provided between the middle portion 4321c and a positioning screw 4323 mounted on the mounting portion 4519 so that both ends of the second spring 4322 abut against the middle portion 4321c and the positioning screw 4323, respectively. As such, under the action of the second spring 4322, the limiting end 4321b of the pawl 4321 can be better engaged with the ratchet teeth 4331 to ensure the limiting end 4321b to be meshed well with the ratchet teeth 4331, thereby avoiding a reverse rotation of the ratchet 433. As shown in FIG. 15, the mounting portion 4519 further includes positioning holes 4519d and 4519e provided corresponding to the rotating shaft 4321d and the positioning screw 4323 for mounting the rotating shaft 4321d and the positioning screw 4323, respectively. The engagement of the pawl 4321 with the ratchet teeth 4331 prevents the ratchet 433 from rotating in reverse. The ratchet 433 and the rotating member 4311 are coaxially arranged, which prevents the rotating member 4311 from rotating in the opposite direction, thereby preventing the striker 411 from being accidentally fired, and providing greater safety.

As shown in FIG. 17, a structural diagram of the inner cylinder is shown according to one embodiment of the invention. FIG. 18 is a partial enlarged view of E in FIG. 4.

As shown in FIG. 4, the inner cylinder 452 is installed inside the outer cylinder body 4511, and the front end of the inner cylinder 452 is connected with the inner wall of the outer cylinder body 4511 through the third sealing member 455 and is locked and limited. In order to allow the inner cylinder 452 to be more stably arranged inside the outer cylinder body 4511, as shown in FIG. 17, a protruding ring 4524 is arranged at the rear end of the inner cylinder 452 away from the third sealing member 455, and a circular positioning flange 456 is arranged on one side of the protruding ring 4524, and one or more air holes 4561 are opened on the circular positioning flange 456 for air to pass through. As shown in FIG. 18, the inner circumference of the circular positioning flange 456 is sleeved on the outer circumference of the inner cylinder 452, and one side is supported by the protruding ring 4524, and the outer circumference of the circular positioning flange 456 is blocked by the end surface of the rear cover 4512 facing the outer cylinder body 4511, so that the circular positioning flange 456 can be limited between the rear cover 4512 and the protruding ring 4524, thereby enhancing the connection stability between the structures. The third sealing member 455 and the circular positioning flange 456 are respectively provided at the front and rear ends of the inner cylinder 452 to support the front and rear ends of the inner cylinder 452, so that the inner cylinder 452 can be more stably fixed inside the outer cylinder body 4511.

According to the embodiments of the invention, in operation, the driving motor in the control device 50 of the nail gun drives the transmission member 431 to rotate. During the rotation process, the rotating member 4311 sequentially contacts with the teeth on the striker 411 from the first engaging pin (movable engaging pin 4312) to engage with the tooth grooves 4112 of the striker 411, thereby driving the striker 411 and the piston 412 to move in the opposite

direction (i.e., the backward direction) of the striking direction inside the inner cylinder 452. During the movement of the piston 412, the volume of the second cavity 4522 gradually becomes smaller, thereby compressing the air in the air chamber 453, and the air pressure in the air chamber 453 gradually rises to store energy. When the rotating member 4311 continues to rotate to form an empty tooth state with the striker 411, the air pressure in the air chamber 453 pushes the piston 412 and the striker 411 are pushed out along the striking direction, so that the striker 411 drives the nail out to complete nail firing.

During the rotation of the rotating member 4311, the ratchet also rotates along with the rotating member 4311, and the pawl 4321 cooperates with the ratchet tooth 4331 on the outer circumference of the ratchet to prevent the ratchet from reversing, thereby avoiding misfiring of the striker during the working process and enhancing safety.

In one exemplary embodiment, the striker can be replaced as follows.

When the nail gun stops working, first removing the nail magazine assembly 30 and the casing 21, then removing the pressure relief member 47 to relieve the pressure inside the air cavity 453, then removing the rear cover 4512 on the rear side of the outer cylinder body 4511, taking out the striking mechanism 41 located inside the inner cylinder body 452, and replacing the striker 411. Meanwhile, if the transmission member 431 also needs to be replaced, then removing the transmission component 431 for replacement, then installing the striking mechanism 41 into the inner cylinder body 452, putting the rear cover 4512 in, and then connecting inflation equipment to the inflation component 46 to inflate the inside of the air cavity 453. After the inflation is completed, reinstalling the casing 21, and installing the corresponding nail magazine assembly 30 to continue nailing.

According to the transmission member and the anti-jamming assembly for the nail gun of the invention, since the transmission member 431 includes a rotating member 4311 and an engaging part 4312. The rotating member is used to be connected to the driving motor of the nail gun and driven to rotate by the driving motor. The engaging part includes a plurality of engaging pins 4312 disposed in the rotating member. The engaging pins 4312 are engaged with the tooth grooves 4112 of the striker 411 to achieve the engagement between the transmission member 431 and the striker 411, so as to drive the striker 411 to move. Compared with the engagement of the gear and the rack, the engagement of the engaging pins 4312 and the tooth grooves 4112 is easier, so the transmission is more stable. When the transmission member 431 and the striker 411 are engaged with each other, the engaging pins 4312 need to be embedded one by one in the tooth grooves 4112 of the striker 411. Conventionally, the engaging pins 4312 and the tooth grooves 4112 may not be completely aligned, resulting in the engaging pins 4312 directly colliding with the tooth block 4111 and being unable to engage and drive normally, resulting in jamming. However, according to the invention, at least one of the engaging pins 4312 is set to be movable. When the movable engaging pin 4312 collides with the tooth block 4111, the movable engaging pin 4312 will move slightly under the action of the impact force and be accurately meshed into the tooth groove 4112, thereby preventing the transmission member 431 and the striker 411 from getting jamming, thereby avoiding personal injury caused by misfiring of the gun nail due to the jamming, and further enhancing safety.

In addition, the limiting structure 433 (e.g., a ratchet) cooperating with the limiting member 432 for limiting the

movement of the striker 411 is directly provided on the transmission member 431, there is no need to provide another structure cooperating with the limiting member 432 on the striker 411, thereby simplifying the structure of the striker 411. Moreover, since there is no direct contact between the limiting member 432 and the striker 411, there is no need to release the limiting relationship between the limiting member 432 when the striker 411 is fired, that is, there is no need to provide a driving device such as a solenoid valve at the limiting member 432 to drive the limiting member 432 to rotate, thereby simplifying the structure and reducing the cost, solving the defects caused by the failure of the solenoid valve, and making the entire nail gun more efficient, stable and safer when working.

The limiting structure 433 in one embodiment is a ratchet coaxially arranged with the rotating member 4311. The ratchet 433 has a number of ratchet teeth 4331 arranged on its outer circumference. The limiting member 432 includes a pawl 4321 that operably engages with the ratchet teeth 4331 of the ratchet 433 and is configured to embed between two adjacent ratchet teeth 4331. The ratchet 433 is arranged to be coaxial with the rotating member 4311, so that the rotating member 4311 and the ratchet 433 can rotate synchronously, and the pawl 4321 engages with the ratchet teeth 4331 to limit the reverse rotation of the rotating member 4311, thereby realizing the movement limit of the striker 411, i.e., preventing the striker 411 from misfiring. Accordingly, the safety of the nail gun is improved. The ratchet 433 and the rotating member 4311 are directly driven by the same driving motor, without the need for an additional power source, which simplifies the structure, reduces the cost, reduces the weight of the nail gun, and makes the nail gun easy to carry and use.

The distance between the ratchet teeth 4331 on the ratchet in one embodiment is smaller than the groove width of the tooth groove 4112 on the striker 411, which has a more stable connection than the pawl 4321 directly mating with the tooth groove 4112. The smaller the distance, the higher the fitting tightness and fitting accuracy of the pawl 4321, which greatly reduces or even eliminates the possibility of the pawl 4321 being detached, thereby reducing the probability of the striker 411 being misfired and improving safety performance.

The energy storage mechanism in one embodiment includes an inner cylinder 452 and an outer cylinder 451, and an air chamber is set between the inner and outer cylinders. The inner cylinder 452 is set inside the outer cylinder body 4511 of the outer cylinder 451. The inner cylinder 452 is provided with the striking mechanism 41. The transmission mechanism 43 drives the striking mechanism 41 to achieve the change of air pressure in the air chamber to achieve nailing. The rear side of the outer cylinder body 4511 is provided with a detachable rear cover 4512, which is convenient for disassembly to maintain or replace the striking mechanism 41 located inside the inner cylinder 452.

The energy storage mechanism 42 in one embodiment is provided with a pressure relief member 47 in fluidic communication with the air chamber 453. When the air pressure in the air chamber 453 increases and exceeds the preset safety critical value, the pressure relief member 47 will automatically open to relieve the pressure in the air chamber 453, so that the air pressure in the air chamber can always be within the safety critical value, ensuring the safety performance of the nail gun. In addition, the energy storage mechanism 42 is also provided with an inflatable member 46

in fluidic communication with the air chamber 453, which can inflate the inside of the air chamber 453 when necessary, which is very convenient.

The outer cylinder 451 in one embodiment is directly integrally formed with the mounting portion 4519, and the mounting portion 4519 is used to mount the transmission member 431. The mounting portion 4519 is made into a universal part. When different nails are needed, it is only necessary to replace the corresponding striker 411 and the transmission member 431 without replacing the entire device, and the applicability is wide. When the user needs to carry out construction in various situations, there is no need to carry a nail gun with various nails, but only to carry the appropriate striker and the transmission member, which is very convenient to carry.

In addition, because of use of a pressure relief member and an inflatable member, when the user needs to replace the striker, the pressure relief member can be removed first to discharge the air inside the air chamber, and then the rear cover body can be disassembled to remove the piston and the striker, and finally the striker can be replaced and reinstalled, and the air chamber can be inflated again through the inflatable member for continued use. If the casing is directly disassembled without first relieving the pressure and exhausting the air chamber, it is easy to cause the striker to misfire, so the pressure relief member can also be used as a safety component to improve the safety of the nail gun.

The foregoing description of the exemplary embodiments of the invention has been presented only for the purposes of illustration and description and is not intended to be exhaustive or to limit the invention to the precise forms disclosed. Many modifications and variations are possible in light of the above teaching.

The embodiments were chosen and described in order to explain the principles of the invention and their practical application so as to enable others skilled in the art to utilize the invention and various embodiments and with various modifications as are suited to the particular use contemplated. Alternative embodiments will become apparent to those skilled in the art to which the invention pertains without departing from its spirit and scope. Accordingly, the scope of the invention is defined by the appended claims rather than the foregoing description and the exemplary embodiments described therein.

Some references, which may include patents, patent applications and various publications, are cited and discussed in the description of this invention. The citation and/or discussion of such references is provided merely to clarify the description of the invention and is not an admission that any such reference is "prior art" to the invention described herein. All references cited and discussed in this specification are incorporated herein by reference in their entireties and to the same extent as if each reference was individually incorporated by reference.

What is claimed is:

1. A transmission member used for a nail gun, comprising: a rotating member configured to be driven by a driving motor to rotate, wherein the rotating member has a plurality of pin mounting holes, wherein the plurality of pin mounting holes comprises at least one movable pin mounting hole; and

an engaging part arranged on the rotating member, wherein the engaging part comprises a plurality of engaging pins installed in the plurality of pin mounting holes, wherein the plurality of engaging pins comprises at least one movable engaging pin moveably installed in at least one movable pin mounting hole, and wherein

two adjacent engaging pins define a gap therebetween, wherein a first engaging pin of the plurality of engaging pins is the movable engaging pin.

2. The transmission member of claim 1, further comprising:

an elastic assembly placed between the movable engaging pin and the rotating member, wherein the elastic assembly comprises a spring with one end abutting against the movable engaging pin, and the other end abutting against the rotating member.

3. The transmission member of claim 2, wherein the at least one movable pin mounting hole is an oblong hole comprising an accommodating cavity, and wherein the spring is placed in the accommodating cavity.

4. The transmission member of claim 3, wherein the remaining pin mounting holes are in a circular shape matching with that of the engaging pins.

5. The transmission member of claim 3, wherein the elastic assembly further comprises a block placed between the spring and the movable engaging pin in the accommodating cavity, and wherein one side of the block facing the spring is provided with a limiting hole in which the spring is inserted, or a limiting column on which the spring is sleeved, and the other side of the block facing the movable engaging pin is provided with an active surface in contact with the movable engaging pin.

6. The transmission member of claim 1, wherein the plurality of engaging pins has n engaging pins, wherein a first gap is formed between the first engaging pin and an adjacent second engaging pin, and among the remaining engaging pins, each engaging pin has a second gap of the same distance with the adjacent engaging pin, and the first gap is larger than the second gap.

7. The transmission member of claim 1, wherein the rotating member is a circular structure having a pair of circular disks concentrically connected to one another to define a space therebetween, and a shaft mounting hole defined in the center thereof, through which the rotating member is installed on the output shaft of the driving motor which operably drives the rotating member to rotate, and wherein the plurality of pin mounting holes is defined on the circumference portion of the rotating member.

8. A nail gun for nailing, comprising:
the transmission member of claim 1.

9. An anti-jamming assembly used for controlling nail striking of a nail gun, comprising:

a striker configured to strike nails out of the nail gun along a striking direction for nailing, wherein the striker comprises a plurality of tooth grooves; and
a transmission member coupled with the striker for driving the striker to move in a direction opposite to the striking direction, wherein the transmission member comprises:

a rotating member configured to be driven by a driving motor to rotate, wherein the rotating member has a plurality of pin mounting holes, wherein the plurality of pin mounting holes comprises at least one movable pin mounting hole; and

an engaging part arranged on the rotating member, wherein the engaging part comprises a plurality of engaging pins installed in the plurality of pin mounting holes, wherein the plurality of engaging pins comprises at least one movable engaging pin moveably installed in at least one movable pin mounting hole, and wherein two adjacent engaging pins define

21

a gap therebetween, wherein a first engaging pin of the plurality of engaging pins is the movable engaging pin; and

wherein during the rotation of the transmission member, the plurality of engaging pins is sequentially meshed with the plurality of tooth grooves to achieve an engagement between the transmission member and the striker.

10. The anti-jamming assembly of claim **9**, wherein each tooth groove has a guiding portion for guiding an engaging pin to enter the tooth groove, and an engaging portion extending from the guiding portion for snap-fitting with the engaging pin to achieve the engagement.

11. The anti-jamming assembly of claim **10**, wherein the guiding portion is formed in an arc-straight-line profile including an inclined arc shape and a straight line being tangent to the inclined arc shape, and wherein the engaging portion includes a retaining edge smoothly extended from the straight line of the guiding portion with a profile matching that of the engaging pin.

12. The anti-jamming assembly of claim **9**, wherein the number of the tooth grooves is greater than or equal to the number of the engaging pins.

13. The anti-jamming assembly of claim **9**, wherein the transmission member further comprises:

an elastic assembly placed between the movable engaging pin and the rotating member, wherein the elastic assembly comprises a spring with one end abutting against the movable engaging pin, and the other end abutting against the rotating member.

14. The anti-jamming assembly of claim **13**, wherein the at least one movable pin mounting hole is an oblong hole

22

comprising an accommodating cavity, and wherein the spring is placed in the accommodating cavity.

15. The anti-jamming assembly of claim **14**, wherein the remaining pin mounting holes are in a circular shape matching with that of the engaging pins.

16. The anti-jamming assembly of claim **14**, wherein the elastic assembly further comprises a block placed between the spring and the movable engaging pin in the accommodating cavity, and wherein one side of the block facing the spring is provided with a limiting hole in which the spring is inserted, or a limiting column on which the spring is sleeved, and the other side of the block facing the movable engaging pin is provided with an active surface in contact with the movable engaging pin.

17. The anti-jamming assembly of claim **9**, wherein the plurality of engaging pins has n engaging pins, wherein a first gap is formed between the first engaging pin and an adjacent second engaging pin, and among the remaining engaging pins, each engaging pin has a second gap of the same distance with the adjacent engaging pin, and the first gap is larger than the second gap.

18. The anti-jamming assembly of claim **9**, wherein the rotating member is a circular structure having a pair of circular disks concentrically connected to one another to define a space therebetween, and a shaft mounting hole defined in the center thereof, through which the rotating member is installed on the output shaft of the driving motor which operably drives the rotating member to rotate, and wherein the plurality of pin mounting holes is defined on the circumference portion of the rotating member.

19. A nail gun for nailing, comprising:
the anti-jamming assembly of claim **9**.
